United States Patent [19]

Chesnut

[11] Patent Number: Des. 405,865

[45] Date of Patent: **Feb. 16, 1999

[54] FISHING POLE

3,309,809 3/1967 Bowker D22/142

[75] Inventor: John M. Chesnut, Grantham, N.H.

Primary Examiner—Doris V. Coles

Attorney, Agent, or Firm—Jeffrey E. Semprebon; Michael J. Weins

[73] Assignee: Lure Launcher Products, LLC,
Grantham, N.H.

[57] CLAIM

[**] Term: 14 Years

The ornamental design for a fishing pole, as shown and described.

[21] Appl. No.: 87,269

DESCRIPTION

[22] Filed: Apr. 29, 1998

FIG. 1 is a perspective view of the fishing pole showing my new design;

[51] LOC (6) Cl. 22-05

FIG. 2 is a right side elevation view thereof, the left side elevation not shown being a mirror image of the side elevation shown;

[52] U.S. Cl. D22/142

FIG. 3 is a front and elevation view thereof;

[58] Field of Search D22/142, 139,
D22/138; 43/18.1, 20, 22, 23

FIG. 4 is a rear end elevation view thereof;

[56] References Cited

FIG. 5 is a top plan view thereof;

U.S. PATENT DOCUMENTS

FIG. 6 is a bottom plan view thereof; and,
